United States Patent Office

Des. 182,036
Patented Feb. 4, 1958

182,036

TISSUE PAPER AND LIKE SHEET MATERIAL

Paul Adolf Muller, Herrliberg, Switzerland

Application November 9, 1955, Serial No. 38,809

Term of patent 14 years

(Cl. D59—2)

FIG. 2

FIG. 3

Fig. 1 is a top plan view of a tissue paper or like sheet material showing my new design,

Fig. 2 is an enlarged fragmentary view of Fig. 1, and
Fig. 3 is an edge view of Fig. 2.

I claim:

The ornamental design for a tissue paper or like sheet material, substantially as shown.
